UNITED STATES PATENT OFFICE.

JOHN L. CHRISTIAN, OF PINNACLE, NORTH CAROLINA.

AUTO UTILITY TABLE.

Application filed April 30, 1924. Serial No. 710,147.

To all whom it may concern:

Be it known that I, JOHN L. CHRISTIAN, a citizen of the United States, residing at Pinnacle, in the county of Stokes and State 5 of North Carolina, have invented new and useful Improvements in Auto Utility Tables, of which the following is a specification.

This invention relates to conveniences or accessories for use in connection with automobiles and has for its object the provision of a novel table designed to be detachably mounted on a door of the vehicle body and movable to extend in a horizontal position to form a writing desk, table for serving refreshments and the like, the device being also well adapted for holding a road or other map in proper position to facilitate reading, there being however no limitations as to the specific use.

20 An important object is the provision of a table attachment which is provided with novel clamping means whereby it may be readily engaged upon a door, the clamping means being furthermore adjustable to fit 25 upon doors of different thicknesses and constructed to avoid scarring or marring the finish of the car.

An additional object is the provision of an attachment of this character which will be simple and inexpensive in manufacture, easy to install, positive in action, efficient, durable and convenient in use and a general improvement in the art.

With the above and other objects and advantages in view the invention consists in the details of construction to be hereinafter more fully described and claimed and illustrated in the accompanying drawings, in which:

40 Figure 1 is a vertical section through an automobile door showing the table applied thereto and in operative position,

Figure 2 is a similar view showing the table swung down into inactive position,

45 Figure 3 is a plan view with the parts arranged as in Figure 1,

Figure 4 is a section on the line 4—4 of Figure 3,

50 Figure 5 is a similar view showing the table swung down,

Figure 6 is a side elevation of the attachment.

Referring more particularly to the drawings the letter A designates a portion of an automobile, and B represents one of the doors thereof.

In carrying out my invention I provide a flat table or board 10 of any desired size, shape and material though necessarily of a length less than the height of the door to 60 which it is intended to be applied. Secured upon the underside of this board is a bracket 11 formed with one or more ears 12 pivotally connected at 13 with one or more ears 14 on a clamping member 15 which has a lateral extension 16 at its upper end. For clamping the device upon the door, I provide a second clamping member 17 which has a lateral extension 18 overlapping the extension 16 of the member 15 and adjustably secured to a bolt 19 which passes through a hole in the extension 16 and through an elongated slot 20 in the extension 18. This bolt carries a wing or thumb nut 21 whereby the two members 15 and 17 75 may be secured and held at any desired distance apart to effect clamping upon a vehicle door of any thickness.

To hold the table in horizontal or extended position I provide a brace designated 80 broadly by the numeral 22 which brace includes a section 23, hinged at 24 upon the member 15, and which further includes a section 25 hinged at 26 upon the underside of the table. The two sections 23 and 25 85 of the brace are connected by a rule joint 27 whereby the brace must be pushed upwardly at its intermediate portion to break the joint and permit swinging down of the table against the inside of the door as 90 shown in Figures 3 and 5.

As vehicle doors do not extend vertically and as they all do not have the same pitch, it is necessary to compensate for variations in order to hold the board or table in horizontal position. In carrying out this feature I provide any necessary number of blocks 28 which are secured by any preferred means upon the lower end of the member 15 and which engage against the inside of the 95 door for holding the member 15 in such position that the table will be horizontal. To avoid marring the finish and upholstering on the inside of the door, it is preferable that the members 15, 16, 17 and 28 100 be covered with felt indicated at 29.

The table may of course be used, constructed, and arranged as above described, though it is desirable to provide a sheet or pane 30 of glass or other transparent material held in place by retaining strips or cleats 31 fastened down onto the table at 110

the ends thereof, this transparent sheet serving as a protection for a map 32 or the like which may be thus displayed for convenient reference.

8 From the foregoing description of the clamping members 15 and 17 and by referring to the illustration thereof, it will be seen that they constitute efficient means for mounting the table upon automobiles of any 10 makes in which the doors may be of widely different thicknesses. The clamping members 15 and 17 might be described as of inverted L-shape and while it is not absolutely essential it is preferable that the connection of the two extensions 16 and 18 be 15 of the dovetail shape clearly disclosed in Figure 6 so as to make the structure more rigid.

From the foregoing description it is believed that the construction, mounting and 20 operation will be clear and the advantages of the device readily apparent without any need for further elaboration.

While I have shown and described the 25 preferred embodiment of my invention it

is of course to be understood that I reserve the right to make such changes in the form, construction and arrangement of parts as will not depart from the spirit of the invention or the scope of the subjoined claim. 30

I claim:

A device of the character described, comprising a table, a pair of inverted L-shaped clamping members adapted to be straddled upon the upper edge of an automobile door, 35 said table being hinged upon one clamping member, and a brace pivotally connected with said clamping member and with the table and provided with a rule joint whereby the brace may be broken to permit the 40 table to swing down into substantially vertical position, and adjustable means on the lower end of said clamping member for engagement against the inside of the door for varying the position of said clamping member to brace the table into horizontal position. 45

In testimony whereof I affix my signature.

JOHN L. CHRISTIAN.
